US00D657341S

(12) **United States Design Patent**
Shao

(10) **Patent No.:** **US D657,341 S**
(45) **Date of Patent:** **** Apr. 10, 2012**

(54) **MOBILE PHONE**

(75) Inventor: **Ying Shao**, Lund (SE)

(73) Assignee: **Sony Ericsson Mobile Communications AB**, Lund (SE)

(**) Term: **14 Years**

(21) Appl. No.: **29/402,270**

(22) Filed: **Sep. 22, 2011**

(30) **Foreign Application Priority Data**

May 13, 2011 (EM) 001276356-0001

(51) **LOC (9) Cl.** **14-03**

(52) **U.S. Cl.** ..... **D14/138 G**

(58) **Field of Classification Search** ..... D14/138 AD, D14/138 G, 138 R, 138 AC, 496, 341, 345, D14/346, 203.7, 203.4, 203.3, 203.1, 248, D14/218, 138 AB, 191; 455/575.1, 556.2, 455/556.1, 575.4, 566, 575.3; D10/65; 379/433.01, 379/433.04, 433.11, 433.12, 433.13
